ATTORNEY

UNITED STATES PATENT OFFICE.

PETER R. KUHN, OF NEW YORK, N. Y.

ELECTRICAL-FIXTURE CONNECTION.

Application filed July 19, 1920. Serial No. 397,263.

To all whom it may concern:

Be it known that I, PETER R. KUHN, a citizen of the United States, and resident of New York, in the county of New York and State of New York, have invented certain new and useful Improvements in Electrical-Fixture Connections, of which the following is a specification.

My present invention comprises improved means for supporting, and providing electrical connections to electroliers or other fixtures. The primary object of the invention is to provide means for the purpose specified comprising cooperating parts adapted to be attached one to the electrolier or other fixture and the other to the ceiling of a building or other support which are of such character that the one part may be readily secured to any one of a variety of standard outlet boxes, such as are commonly employed in electrical construction work, while the other parts may be readily secured to the end of an electrolier of various standard constructions, and the two parts may be readily coupled together, and when coupled together provide a mechanical support for the electrolier or like structure which is rigid and possesses the necessary mechanical strength, and which at the same time provides simple and effective electrical connections between the conductors of the electrolier or like structure and the supply conductors extending into the metallic outlet box through the wall of the latter.

The various features of novelty which characterize my invention are pointed out with particularity in the claims annexed to and forming a part of this specification. For a better understanding of the invention however, the advantages possessed by it, and specific objects attained with its use, reference should be had to the accompanying drawings and descriptive matter in which I have illustrated and described a preferred embodiment of the invention.

Of the drawings:

Fig. 1 is an elevation with parts broken away of a portion of a ceiling and electrolier connected thereto.

Fig. 2 is a section on the line 2—2 of Fig. 1.

Fig. 3 is a section on the line 3—3 of Fig. 1.

Fig. 4 is a section taken similarly to Fig.

1, but showing a portion only of the apparatus shown in Fig. 1.

Fig. 5 is a sectional elevation of a portion of the apparatus shown in Fig. 1, with the parts in an initial stage of the coupling operation, and

Fig. 6 is a section taken with the parts in the same relative position shown in Fig. 5, and the other member of the connector in section on the line 6—6 of Fig. 1, and with the inner member in section on the line 6^a of Fig. 1.

In the drawings A represents a metallic ceiling junction box in one of the standard forms in common use with which my present invention is especially adapted for use. As shown the junction box A is in the form of a shallow inverted cup imbedded in a ceiling, and with its lower edge or rim flush with the ceiling surface B. Centrally secured in the junction box A is the corresponding member C of my improved connector. As shown, the member C which is preferably formed of some mechanically strong insulating material, as vulcanized fibre, bakelite or the like, comprises a flanged base through which pass screws D by which the part C is secured to the junction box. The holes through the members C for the screws D are so arranged that these screws may be threaded into the tapped apertures commonly provided for fixture attachment in a junction box of the type shown. As shown also, the part C is preferably made with an axial passage C¹⁰ threaded at its upper end to permit the part C to be screwed on to the pipe support or hanger which projects centrally through the top wall of one standard form of junction box.

The part C comprises a cylindrical body-portion C² having a pair of diametrically opposed longitudinal ribs C³ extending from top to bottom of the body-portion and also having a pair of ribs or lugs C⁶ projecting from the lower end of the body-portion C² between the ribs C³. The ribs C³ are cut-away in their upper portions to provide recessed seats C⁴, and shoulders C⁵, one at one side of each seat C⁴. Metallic contact pieces E are secured to the part C. As shown the body-portions of the contact members E are received in corresponding shallow grooves C⁷ formed at the opposite sides of

the body C^2 and the outwardly bent upper end of each member E is received in a recess C^1 formed in the flanged portion of the member C . The contacts E are secured 5 in place by screws E' and the latter also serve to connect to the contacts E' the corresponding conductors K which enter the junction box A through a conduit J secured to the latter in the usual manner.

10 Each contact member E is provided at its lower end with a resilient back turned or hook portion E^{10} .

Cooperating with the connector part C is a connector part F secured to the stem H of the chandelier or like fixture. The part F is shown as in the form of a cup-shaped member forming a cylindrical socket receiving the body-portion C^2 of the part C when the parts are coupled together. 15 As shown the stem H of the chandelier is screwed into a threaded aperture provided for the purpose in the bottom of the member F which may advantageously be made of the same material as the member C . At 20 its upper end the member F is provided with a pair of diametrically opposed internal ribs F' , and with a second pair of diametrically opposed internal ribs F^2 . The parts are so proportioned that the inner 25 surfaces of the ribs F^1 and F^2 fit snugly about the cylindrical body-portion C^2 of the coupling part C , while the outer surfaces of the ribs C^3 and C^6 fit snugly against the inner wall of the cavity in the member 30 F below the projections F' and F^2 . Mounted in the member F are a couple of metallic contact members G shown as secured in place by screws G' , the heads of which bear against metallic contact members G^2 received in 35 recesses F^6 formed in the outer surface of the member F . Screws G^3 serve to connect the ends of the electrolier conductors I against the plates G^2 and thus connect the conductors I to the contacts G . As shown 40 each conductor I extends from the cavity of the member F to the recess F^8 through a corresponding aperture F^4 formed in the member F . The contacts G are formed at 45 their upper ends with resilient down-turned or hook portions G^{10} which take over the portions F^{10} of the contacts F as shown in Fig. 1 when the connecting parts are coupled together.

In assembling the apparatus, the member F is moved axially on to the body C^2 of the member C to enter the shoulders F' of the member F between the ribs C^3 and the lugs C^6 of the member C until the lower edge of each rib F^1 is above the upper edge 55 of the corresponding shoulder C^5 , after which the member F is rotated in a clockwise direction about the member C to bring the lower ends of the ribs F^1 into engagement with the seat C^4 . In the initial upward movement of the member F relative

to the member C the contacts E and G move alongside of one another, but the rotation of the member F relative to the member C to bring the lugs F^1 above the seats C^4 brings the contacts into the position shown 70 in Fig. 1 and Fig. 2 wherein each hook G^{10} is between the body of the corresponding contact E and its hook E^{10} , and each hook E^{10} is between the body of the corresponding contact G and its hook G^{10} . Advantageously the hooks G^{10} and E^{10} in their unflexed condition are not parallel to the bodies of the contacts, but are inclined as shown in Fig. 5, so that when the contacts 75 engage as shown in Figs. 1 and 3, the resiliency of the metal of the contacts insures a spring pressure engagement. With the ribs C^3 cut away as shown to provide the seats C^4 and shoulders C^5 , the member F must be rotated in a clockwise direction to 80 couple the parts together and in the reverse direction to uncouple them. To insure the easy assembling of the apparatus with each lug F at the proper side of a rib C^3 , the ribs C^3 and C^6 are unevenly spaced apart 85 as shown in Fig. 6 so that a lug F^2 can enter the groove at the left hand side, but cannot enter the groove at the right hand side of either lug C^3 . To prevent accidental displacement of the parts when coupled together and to add rigidity to the coupled connection, I preferably provide means for detachably clamping the parts together. As 90 shown the means provided for this purpose comprises a screw L threaded through an opening in the bottom wall of the member F and bearing against the end of the member C^2 . M represents a canopy of conventional form secured, as by the screw M^1 , on the electrolier stem H and serving to provide an ornamental cover for the outlet 95 box and coupling.

Among the special advantages of the construction disclosed are the following:

The connectors made in the single size 110 and style can be used to connect an electrolier or like fixture of any one of numerous standard types into an outlet box which may be of any one of a number of standard constructions. Owing to the longitudinal 115 displacement of the lugs F^2 and C^6 in the assembled structure, the lengths of the rib C^3 and the location and relative arrangement of the metallic contact parts, the parts C and F telescope so as to provide the equivalent of an elongated cylindrical bearing or contact surface. This prevents any injurious relative movement of the contacts resulting from swaying motion of the electrolier and tending to dislocate or weaken 120 the structure. The rigidity of the parts is enhanced of course by the use of a clamping device such as is formed by the screw L . The coupling parts can be readily attached 125 to the outlet boxes and electrolier or like 130

fixtures and are available for use equally well in new constructions or in structures already built and having outlet boxes of standard form. After the connector parts are secured in place, the electrolier or other fixture can be quickly and easily attached to its ceiling support and when so attached may be readily detached if occasion requires, provided the clamping screw L is loosened but with the latter screwed home, the apparatus cannot be accidentally displaced and detached. The connection has excellent electrical and insulating characteristics and if the connector parts are made of non-inflammable material as they should be, the construction is practically fire-proof. While in accordance with the provisions of the statutes, I have illustrated and described the best form of my invention now known to me, it will be apparent to those skilled in the art that changes may be made in the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent is:—

1. A connector for suspending an electric fixture comprising a part formed of insulating material and adapted to be secured in a standard ceiling outlet box and a co-operating part of insulating material adapted to be secured to the fixture, one of said parts being tubular and telescopically receiving the other, said tubular part having its inner wall shaped to provide an axially elongated cylindrical bearing surface, and the other part being shaped to provide an external axially elongated cylindrical bearing surface adapted to fit snugly in the first mentioned bearing surface, one of said parts being formed with a lug projecting from the bearing surface of the part and the other part being cut away to form a bayonet joint-like groove in its bearing surface, whereby the parts may be axially moved together, with said lug received in said groove, and may then be rotated relative to one another to bring the parts into position in which the end edge of said lug and the transverse edge wall of said slot form shoulders co-operating to prevent axial displacement of the parts, electrical contact members carried by and located within said tubular part and cooperating electrical contact members carried by the other part and brought into engagement with the first-mentioned contact member by the movement of said parts into the relative position in which said shoulders prevent axial displacement of said parts.

2. An electrical connector of the character

specified comprising a tubular body of insulating material and a second body of insulating material extending into the tubular part and having a diameter less than the internal diameter of said tubular body, and means comprising integral internal projections from the tubular body and integral external projections on said second body, providing axially elongated and circumferentially extending bearing surfaces between said bodies and a bayonet joint connection for locking said bodies against axial displacement in one direction in one angular adjustment of the parts, and cooperating metallic electrical contact members secured to said parts so as to lie between said projections and engage with one another when said parts are in the position in which they are locked against axial displacement.

3. An electrical connector comprising a tubular body of insulating material and a second body of insulating material adapted to extend into said tubular body and of a diameter less than the internal diameter of the tubular body, and means comprising internal projections on the tubular body and external projections on second body for providing axially elongated and circumferentially extending contact surfaces between said bodies and a bayonet joint connection for locking said bodies against axial displacement in one direction in one angular adjustment of the bodies, metallic electrical contact members carried by said bodies and located between said projections and brought into engagement with one another by the movement of said bodies into the position in which they are locked against axial displacement in the one direction, and means for releasably holding said bodies against axial displacement in a direction opposite to the first-mentioned direction.

4. An electrical connector comprising a tubular body of insulating material formed with angularly spaced apart internal projections at one end and a second body of insulating material of a diameter permitting its insertion in said tubular body between said projections and provided with external longitudinally-extending ribs passing between said spaced apart projections and each cut-away at one side to provide a recessed seat for a corresponding one of said projections when axially inserted in said tubular body and rotated to couple said bodies together, said second body being provided at its end entering said tubular body with projections located between and spaced apart from said ribs, whereby circumferentially extending bearing surfaces between the two bodies are provided at each end of the portion of the second body received in said tubular body, and electrical contact members secured to the two members and engaging one another between said bearing surfaces.

surfaces when said bodies are coupled together to prevent the axial movement of the parts together except when the cut-away side of each rib is alongside the co-operating projection of the tubular part.

5. An electrical connector comprising a tubular body of insulating material formed with angularly spaced internal projections at one end and a second body of insulating material of a diameter permitting its insertion in said tubular part between said projections and provided with external longitudinally-extending ribs passing between said spaced apart projections and each cut-away at one side to provide a recessed seat for a corresponding one of said projections when axially inserted in said tubular part and rotated to couple the parts together, said second body being provided at its entering end with projections located be-

tween, and spaced apart from said ribs whereby circumferentially extending bearing surfaces between the two bodies are provided at each end of the portion of the second body received in said tubular part, and electrical contact members secured to the two members and engaging one another between said bearing surfaces when said bodies are coupled together, said projections and ribs being so angularly proportioned and disposed as to prevent the axial movement together of the bodies except when the cut-away side of each rib is alongside a projection of said tubular body adapted to engage said recessed seat.

Signed at New York, in the county of New York and State of New York, this 17th day of July, A. D. 1920.

PETER R. KUHN.
